UNITED STATES PATENT OFFICE.

WILLIAM TREWHELLA, OF TRENTHAM, VICTORIA, AUSTRALIA, ASSIGNOR
TO HIMSELF AND BENJAMIN TREWHELLA, OF TRENTHAM, VICTORIA,
AUSTRALIA.

LIFTING-JACK.

No. 821,769.

Specification of Letters Patent.

Patented May 29, 1906.

Application filed October 17, 1904. Serial No. 228,770.

To all whom it may concern:

Be it known that I, WILLIAM TREWHELLA, a subject of the King of Great Britain, residing at Trentham, in the State of Victoria, 5 Commonwealth of Australia, have invented a Lifting-Jack, of which the following is a specification.

This invention relates to lifting-jacks, and in particular to lever-operated jacks in which 10 the casing is employed to carry the weight on a claw or rest or on the top, said casing being raised or lowered by means of pawl-and-ratchet mechanism or hydraulically.

The especial feature of the invention is to 15 provide a load-carrying casing that is non-rotatable, the casing being constructed to slide on and be guided by the standard or rack and provided, substantially as shown in the accompanying drawings, with a top plate 20 and three or more rests arranged thereon at different levels and in different vertical planes. The effect of this is that the weight may readily be taken at various heights, and the lever can be worked in narrow passages by 25 employing one of the rests, which would project at right angles to said passage, so that the lever could be operated longitudinally therein.

The accompanying drawings illustrate the 30 invention and comprise, in Figure 1, a side elevation, Fig. 2 a front elevation, and Fig. 3 a plan, of a lifting-jack which can be operated by pawl-and-ratchet mechanism in the well-known manner and formed with five 35 rests, including one formed by the top of the casing. Figs. 4, 5, and 6 are respectively similar views of a lifting-jack which can be operated hydraulically in the well-known manner and provided with four rests, including the 40 top.

Referring now to the drawings, A represents the rack-bar, which in the kind of jack referred to, Figs. 1, 2, and 3, is stationary, and B the ram-cylinder of a hydraulic jack shown in Figs. 4, 5, and 6. The casing C, which is 45 adapted to be raised and lowered by the power employed, is provided with a number of rests D E F G H, formed on the different sides thereof, each being adapted to take the weight at different levels, as before mentioned. 50

J represents the squared end of a rocker or crank pin to which a lever or pump-handle may be attached to work the jack. Having now particularly described and ascertained the nature of my said invention 55 and in what manner the same is to be performed, I declare that what I claim is—

1. A lifting-jack of the type described comprising a support and a non-rotatable casing 60 slidable vertically thereon, said casing closed at top to form one rest for a load to be lifted and provided between its upper and lower ends with a plurality of other fixed rests at different levels, for the purposes set forth.

2. A lifting-jack of the type described comprising a support and a non-rotatable casing 65 slidable vertically thereon, said casing closed at top to form one rest for a load to be lifted, and provided between its upper and lower ends with a plurality of other fixed rests at 70 different levels and in different vertical planes, for the purposes set forth.

In testimony whereof I have hereunto set my hand in presence of two subscribing witnesses.

WILLIAM TREWHELLA.
